BOILER

Wendel M. Roth, Trenton, N. J.

Application March 8, 1937, Serial No. 129,697

8 Claims. (Cl. 122—225)

This invention relates to new and useful improvements in liquid heating apparatus and more particularly to a novel boiler construction.

The principal object of the present invention is to provide a boiler construction which broadly consists of a plurality of vertical boiler sections and a main water receiver common to all of the sections.

Another important object of the invention is to provide a sectional boiler construction broadly consisting of a main water receiver and a plurality of vertical boiler sections extending laterally therefrom.

Still another important object of the invention is to provide a boiler construction in which a plurality of vertical water heating sections are provided in conjunction with a common water receiver and wherein the sections are of duplicate construction permitting replacement without regard to location in the boiler.

A further object is to provide a boiler construction of the multiple vertical sectional type wherein in a main water receiver is provided common to all of the sections and in which an auxiliary steam chamber is afforded which is available when the boiler is employed for steam heating.

Still a further object of the invention is to provide a boiler wherein the vertical sections are of identical construction and which do not have any water connection between the same.

Another important object of the invention is to provide a boiler in which a one-way circulation is maintained.

Other important objects and advantages reside in the simplicity of construction affording manufacture at a low cost, accommodations for general utility water heating coils and the special treatment of the water in small quantities to promote thorough heating thereof, as well as numerous other features which will become apparent to the reader of the following specification.

In the drawings:—

Figure 1 represents a side elevational view of the boiler.

Figure 2 is a vertical sectional view transversely through the vertical sections.

Figure 3 is a vertical sectional view on the line 3—3 of Figure 1.

Figure 4 is a fragmentary horizontal sectional view substantially on the line 4—4 of Figure 3.

Figure 5 is a vertical sectional view substantially on the line 5—5 of Figure 3.

Figure 6 is a side elevational view of the water receiver.

Figure 7 is a side elevational view of one of the sections.

Figure 8 is a rear elevational view of one of the sections, facing the water receiver.

Figure 9 is a front elevational view of one of the sections, facing the water receiver.

Figure 10 is a vertical sectional view on the line 10—10 of Figure 7.

Figure 11 is a fragmentary sectional view on the line 11—11 of Figure 7.

Figure 12 is a horizontal sectional view on the line 12—12 of Figure 7.

Figure 13 is an enlarged detailed sectional view substantially on the line 13—13 of Figure 8.

Referring to the drawings wherein like numerals designate like parts, it can be seen especially in Figure 3, that the boiler involves a water receiver 5 which is common to all of the sections 6. In fact, these sections 6 extend laterally from the receiver 5 as suggested in Figure 4 and for a twin type boiler, these sections may extend from opposite sides of the receiver 5 with but little reformation of the receiver, and connections to the same.

As is shown in Figure 5, numeral 7 denotes the water supply line to the chamber 8 at the bottom of the receiver 5. The chamber 8 is divided from the chamber 9 by the horizontal partition 10 having the openings 11 therein.

Extending upwardly from the partition 10 is the vertical partition 12 dividing the narrow lower portion of the receiver 5 into the passageways 13 and 14. In the wider upper portion of the receiver 5 can be mounted the general utility water heating coil or coils 15 upon which is the water level 16. The upper portion of the receiver 5 can be regarded as the steam dome when the boiler is being used in steam heating. At the top of the receiver 5 is the outlet 17 for hot water or steam as the heating system may call for.

Each of the sections 6 consists of a main horizontal passageway 18 at its lower portion from which extend the outwardly disposed outside water conduits 19—20 and the inside water conduits 21—22. The conduits 21—22 merge together in the manifold 23 and from this manifold rises the neck 24, rising into the main chamber 25 of the sections into which empties the conduits 19—20. Thus as water is received in the passageway 18 it will rise through four separate conduits and the water thus divided into these small quantities will more thoroughly heat than when water is passed in one column through the heating zone.

It can also be seen that the manifold 23, passageway 18, and conduits 21-22 define an opening in each of the sections 6 which openings combined define a combustion chamber 26 and it can further be observed in Figure 3 that the upper portion of each of the conduits 19-20 is spaced from the top portion of the manifold 23 to afford lateral passageways 27-27 for the hot products of combustion.

As can be seen in Figure 8, as well as in Figure 9, the conduits 20-22 and 21 are substantially narrower than the conduit 19 and this is also true of the manifold 23 and main water compartment 25. Thus heat from the combustion chamber 26 can strike the sides of the conduits 21, 22 and 20 and the products of combustion can pass upwardly between the manifold 23 and side walls of the water compartment 25.

At this point attention is directed to Figures 7 and 8 showing the heat conducting fins which also serve as baffles.

It can be seen, that the products of combustion passing upwardly between the sections will first strike the horizontal centrally located baffles 28 which will cause lateral spreading of the hot gases. From the ends of this baffle 28 the gases will rise until they strike the laterally disposed baffles 29 which will cause the hot gases to pass inwardly above the baffle 28 and longitudinally along the fins 30 until the inner area 31 is reached where the gases pass upwardly until they strike the second centrally located baffle 32 which again causes lateral spreading of the hot gases longitudinally along the fins 33 until the lateral areas 34 are reached wherein the gases pass upwardly and strike against the short baffles 35-35 which again causes inward movement of the gases through the fins 36. The openings 37-38 in the upper portions of the sections 6 define horizontal flues for the products of combustion having their outlets at the manifold 39 and from which the flue pipe 40 extends.

As shown in Figure 3, numeral 41 represents a connection between a section and the receiver 5 forming the water inlet to the receiver, while numeral 42 represents another connection of tubular construction between the same section and the receiver and forming the outlet of the receiver to the passageway 18.

Connecting the upper end of each of the sections 6 to the upper portion of the receiver 5 is the third connection generally referred to by numeral 43 and this connects with the conduit 44 which inclines toward the receiver 5.

Each of these connections 41, 42 and 44 consists of a tubular member 45 externally threaded to engage into the corresponding section 6 and more specifically a boss formation 6a thereof and it is preferable that these bosses 6a be countersunk as at 6b to receive tapering teats 5a on the inner wall of the receiver 5. The receiver end of the tube 45 is flanged as at 46 to abut the wall of the receiver 5 and is internally provided with wrench receiving recesses 47. A suitable wrench or the like can be inserted into the upper portion of the receiver 5 after the trap doors 48 have been removed for engaging the tubes 45 and unscrewing the same to permit detachment of the desired section 6. The connections 41 can also be reached through the trap door openings in the top of the receiver 5, while openings are provided in the outer wall of the receiver adjacent the bottom thereof to permit access to the connection 42. These openings being normally plugged as at 49.

As is clearly shown in the drawings, the entire boiler is provided with an external shell consisting of the top wall 50, front and rear walls 53-54, respectively, and the side walls 51-52. It can be seen that the front wall of the shell has a plurality of elongated vertically disposed openings therein normally closed by the plates 55, which plates can be removed to permit access to the fins and baffles shown in Figure 7 whereby the same can be easily cleaned. It can also be seen that the combustion chamber is provided with a cover plate 56 at the front wall 54.

Opposite ends of the chamber 8 at the bottom of the water receiver 5 are provided with openings, one of which is plugged as at 57. This plug can be removed for permitting easy cleaning out of the said chamber 8 when mud and other refuse collect therein.

In the operation of this boiler, it can be seen that when water heat is to be the service, the receiver is filled to approximately the top thereof and the fire is started in the combustion chamber 26. Water will rise in the chamber 25 and pass into the top of the receiver 5, as water descends in the receiver 5 to pass through the outlet 42 to the passageways 18 of the sections 6.

As heat directly passes between the conduits 20-22 and heats the adjacent walls of the sections 6 and receiver 5, the partition 12 in the lower portion of the receiver is used to divide the lower portion of the receiver into the compartments 13-14. Thus water heated in the compartment 13 can rise while water in the compartment 14 is free to descend and pass through the openings 11 to reach the chamber 8 and outlet 42. Thus this circulation in the lower portion of the receiver 5 is contemplated to reduce friction and not hinder the one-way circulation of water from the receiver through each individual section 6.

As water passes into the passageway 18, it rises through all four of the conduits 19, 20, 21 and 22 and in these small columns water is thoroughly heated, the water from the conduits 21-22, mixing in the manifold 23, while water from the conduits 19-20 mixes with the water from the manifold 23 as it emerges from the neck 24.

At this point it will be observed, that at all points where sediment can occur the surface is inclined so that all sediment will either be kept in circulation or settle upon the lowest point in the boiler which, of course, will be the bottom of the chamber 8 where the sludge, mud and other refuse can be easily reached.

When the boiler is being used for steam heating service, the water level is lower at approximately the line 46 and as the water vapor leaves the surface of the water, it strikes against the hot transverse flues 37 in the section 6. This action of the water vapors against these hot transverse passageways 37 actually causes a flashing of the water vapors into a dry steam which passes upwardly along the conduit 44 to the steam chamber or dome which will be above the water level in the receiver 5.

It should also be taken into consideration, that in the event any one of the sections 6 becomes defective, the connections 41, 42 and 43 can be disconnected after first draining the water from the boiler and the corresponding section 6 removed, after which the opening in the inner wall of the receiver 5 for these connections of the defective sections can be plugged, and the system again filled with water and operation started. Of course, it is not necessary that the

defective sections actually be removed from the shell, as a plug may be driven into the tubular members 45 of the connections 41, 42 and 43 after water has been drained from the boiler so as to completely shut off that particular section, but this will not disrupt the service of the boiler in regard to the remaining sections 6. At a later time, the defective section can be replaced.

This boiler, while primarily meant for oil or heating gas use can readily be adapted to other fuel consumption by a few minor changes which do not affect the scope of the invention.

Due to the construction and disposition of the baffles on the sections 6 (see Fig. 3) manifolds 15 23 are brought in close proximity of the fire without restricting the necessary combustion area. This allows for rapid heat absorption and greatly increases the efficiency of the boiler.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. A boiler comprising a main water receiver, and removable water heating sections extending laterally from the receiver, said sections having 30 openings in the lower portions thereof which when the sections are assembled together define a combustion chamber.

2. A boiler comprising a main water receiver, and removable water heating sections extending 35 laterally from the receiver, said receiver having water inlets and outlets at its upper and lower portions communicating the sections with the receiver, and a partition in the lower portion thereof permitting water on the sections side 40 thereof to move upwardly as it is heated without friction on water passing downwardly on the opposite side of the partition to the outlet.

3. A boiler comprising a water receiver extending along a single side thereof, and water-45 heating sections extending laterally from said receiver in vertically disposed side-by-side relation and communicating at the upper and lower ends thereof with said receiver, said sections having openings therethrough mating and providing a combustion chamber.

4. A boiler comprising a main water receiver, and removable water-heating sections extending laterally from the receiver, said receiver having water inlets and outlets at its upper and lower 55 portions communicating the sections with the receiver, a partition in the lower portion of the receiver permitting water on the sections side to move upwardly as it is heated without friction on water passing downwardly on the opposite side of the partition to the outlet, and a water-heating coil mounted in said receiver above said

partition for location in the path of the upwardly and downwardly moving water.

5. A boiler comprising a water receiver extending along a single side thereof, and water-heating sections extending laterally from said receiver in vertically disposed side-by-side relation and communicating at the upper and lower ends thereof with said receiver, said sections having openings therethrough mating and providing a combustion chamber around which the water 10 in said sections is caused to circulate, and partitions in each section dividing the same into multiple passageways causing the water to circulate in multiple channels and thereby providing for thorough heating.

6. A boiler comprising a water receiver, and water-heating sections extending laterally from said receiver in vertically disposed side-by-side relation and communicating at the upper and lower ends thereof with said receiver, said sections 15 having base portions engaging and apertured to provide a combustion chamber extending through the same, and said sections above said base portions being reduced in thickness to provide narrow upstanding water tubes spaced apart for the 20 passage of heat from said combustion chamber therebetween.

7. A boiler comprising a water receiver, and water-heating sections extending laterally from said receiver in vertically disposed side-by-side 30 relation and communicating at the upper and lower ends thereof with said receiver, said sections having base portions engaging and apertured to provide a combustion chamber extending through the same, and said sections above said base 35 portions being reduced in thickness to provide narrow upstanding water tubes spaced apart for the passage of heat from said combustion chamber therebetween, the reduced portions having external heat baffling fins thereon directing the 40 heat passing between said reduced portions in tortuous paths.

8. A boiler comprising a water receiver, and water-heating sections extending laterally from said receiver in vertically disposed side-by-side 45 relation and communicating at the upper and lower ends thereof with said receiver, said sections having base portions engaging and apertured to provide a combustion chamber extending through the same, and said sections above 50 said base portions being reduced in thickness to provide narrow upstanding water tubes spaced apart for the passage of heat from said combustion chamber therebetween, the reduced portions having external heat baffling fins thereon 55 directing the heat passing between said reduced portions in tortuous paths, said fins being spaced apart vertically and endwise to cause the heat to pass back and forth along the same as said heat rises.

WENDEL M. ROTH.
